LUBRICATING SYSTEM FOR TURBINES AND THE LIKE.

1,291,374.

Specification of Letters Patent. Patented Jan. 14, 1919.

Application filed March 27, 1917. Serial No. 157,806.

To all whom it may concern:

Be it known that I, OLIVER D. H. BENTLEY, a citizen of the United States, residing at West Roxbury, in the county of Suffolk and State of Massachusetts, have invented certain new and useful Improvements in Lubricating Systems for Turbines and the like; and I do hereby declare the following to be a full, clear, and exact description of the invention, such as will enable others skilled in the art to which it appertains to make and use the same.

When a steam turbine is in operation, there is always a difference of pressure between the interior of the casing and the atmosphere. Where the turbine is used without a condenser, the pressure within the casing is above atmosphere and the steam or vapor within the casing tends to flow along the bearing through which the turbine shaft emerges from the casing, thus displacing or mingling with the oil and interfering with the proper lubrication of the bearing.

Where a condenser is employed the pressure within the casing is below atmosphere and the tendency is for the outside air to work through the bearing into the casing with a similar interference with the lubrication. In order to avoid this escape of steam from within the casing to the outer air, or the passage of air into the casing, it has heretofore been found necessary to employ complex and bulky packing-devices and to provide for diverting or collecting such water or oil as may be carried through the bearing under the differences of pressure which exist at its opposite ends.

The object of the present invention is to produce a lubricating system, suitable for use with a steam-turbine or other machine in which a rotary shaft passes from a region of higher pressure to a region of lower pressure, in which the passage of fluid through the shaft-bearing from the region of higher pressure is prevented or minimized, without the use of complex packing-devices or other bulky or expensive constructions.

To the foregoing end it is proposed, in accordance with the present invention, to prevent the passage of the fluid above referred to by balancing, against the pressure of such fluid, the pressure of the lubricating fluid with which the shaft-bearing is supplied, the two balanced pressures resulting

in an equilibrium whereby movement of fluid in either direction is prevented or minimized at the point of emergence of the shaft from the region of higher pressure. In the preferred embodiment of the invention the balance of pressures is maintained automatically, and the pressure under which the lubricant is introduced results in a constant flow of lubricant through the bearing, whereby constant and copious lubrication is insured.

Other objects of the invention, and the features of construction by which they are attained, will be set forth in connection with the following description of the illustrated embodiment of the invention.

The accompanying drawing is a diagrammatic view, in vertical section, showing a steam-turbine operating without a condenser and equipped with the lubricating apparatus of the present invention in one form in which its use is contemplated.

The invention is illustrated as embodied in, and applied to, a turbine of a well known impact type, having the usual rotor or wheel 1 which turns within a casing 2 which supports the usual stationary elements of the turbine. The rotor is mounted upon a shaft 3 by which the power is transmitted to the exterior of the casing. The exhaust steam is discharged first into the casing, and escapes thence through an exhaust opening 31 in the usual manner.

In turbines of the illustrated type it has been common heretofore to provide packed joints at the points of emergence of the shaft from the casing, and to separate the bearings, in which the shaft turns and is supported, from these joints by a space sufficient to permit the escape of any steam or condensed mixture which escapes through the packing. By the use of the present invention, however, the bulk and complication of such an arrangement is avoided, and the bearing-bushings 4, in which the shaft turns, are mounted directly in sleeves 5 projecting integrally from the walls of the casing, so that the bearings are subject, at their inner ends, to whatever pressure may be within the casing. Where the turbine is not used with an exhaust-condenser there is a continuous pressure of the exhaust-steam within the casing, although this pressure varies, in any given installation, according to the volume

and the temperature of the steam which is being used at the moment to drive the turbine.

- The lubricating oil is contained in a reservoir 6 of sufficient capacity to provide for a long period of operation of the turbine, and the lubricant is drawn from the reservoir by a pump 7, through an outlet-pipe 8 which connects the intake of the pump with a point 10 in the lower part of the reservoir. The pump 7 may be a rotary pump or gear-pump of any ordinary or suitable form, and it is actuated by connection with the reduced end of the shaft 3, as shown in the drawing.
- 15 The pump produces a constant flow of oil, which is discharged through pipes 9 and 10, and through the intermediate regulating-device which will be presently described, into annular channels 11 formed, respectively, near the inner ends of the bearing-bushings 4. The oil so forced into these channels tends to flow in both directions between the adjacent surfaces of the shaft and each bearing-bushing, but the flow of 25 the oil inwardly, or toward the casing, is prevented by the pressure of the steam or vapor within the turbine casing. Accordingly, the oil flows only outwardly through the bearings so as to lubricate them substantially from end to end with a constantly renewed supply of oil.
- 30 The automatic means for balancing, with approximate accuracy, the pressures of the steam and the oil comprise a diaphragm casing having lower and upper members 12 and 13, respectively, secured together peripherally so as to form a chamber which is divided by a flexible diaphragm 14 clamped, at its edge, between the casing-members.
- 35 40 The pipes 9 and 10 communicate with the space beneath the diaphragm, while the space above the diaphragm is connected, by a pipe 15, with the turbine-casing. The diaphragm-casing is also connected, at its lower part, with the oil-reservoir 6 by a passage 16, and the entrance to this passage is controlled by an escape-valve 17 which is attached to the diaphragm 14.
- 45 The pump 7 is made of such capacity that it produces, at all times, a flow of oil in excess of that which will pass through the shaft-bearings. The surplus oil is discharged through the passage 16, and thus returned to the reservoir. The flow through 50 this passage is controlled by the valve 17, in accordance with the relative degrees of pressure above and below the diaphragm. Assuming that the normal position of the diaphragm and the valve is such that the latter 55 is somewhat raised from its seat, as shown in the drawings, whenever the pressure of the oil beneath the diaphragm tends to exceed the steam-pressure, communicated through the pipe 15, the diaphragm bulges upwardly, thus moving the escape-valve to

a more widely open position and relieving the excessive oil-pressure by diminishing the resistance to the escape of the surplus oil. On the other hand, if the steam-pressure rises or the efficiency of the oil pump is, 70 through any cause, diminished so that the oil-pressure beneath the diaphragm tends to fall below the steam-pressure, the opposite effect results and the escape-valve is moved to a more nearly closed position, thus building up the oil-pressure so as to cause it to equal the steam-pressure.

75 Since it is not practically possible to so construct the diaphragm and the escape-valve that they will secure exactly the desired result, means are preferably provided for adjusting the action of these parts. To this end a leaf-spring 18 may be fixed, at one end, in the diaphragm-casing and connected at the other end, with the 80 middle of the diaphragm. An adjusting-screw 19 bears against the upper surface of the spring 18, and by manipulation of this screw the effect of the spring upon the diaphragm may be adjusted to secure any desired conditions of balance.

85 The ideal operation of the apparatus is one in which there is an exact balance between the steam-pressure and the oil-pressure. Since it is not practically possible to 90 secure this absolute balance under varying conditions of operation, it is preferable to so adjust the parts that whatever slight difference may occur in the two pressures will be in favor of the steam pressure, so that 95 whatever leakage occurs will be leakage of steam or water outwardly, rather than an inward leakage of oil. Such leakage, occurring under a very slight difference of pressures within and without the casing, 100 may be rendered practically negligible by the use of a simple form of packing around the shaft at the inner end of each bearing-bushing. In the drawing packing-rings 24 are shown as seated in the inner portions 105 of the sleeves 5, and the bushings 4 are arranged to be used as glands to compress these packing-rings, the bushings being movable endwise in the sleeves, and being adjustably secured in place by screws 25 110 passing through flanges at the outer ends of the bushings. Endwise movement or thrust in the turbine-shaft is sustained by thrust-collars 26, screwed on the ends of the shaft and bearing against the outer ends of the 115 bearing-bushings.

120 To assist in adjusting the lubricating-apparatus to secure the desired balance or slight difference of pressures, pressure-indicating means may be employed to indicate 125 the relative degrees of pressure in the turbine-casing and in the lubricating system. For this purpose the drawing shows a device in the nature of a U-tube. One limb 20 of this tube is made of glass, while the other 130

and shorter limb is formed by a pipe 21 which communicates with the interior of the turbine-casing. The upper end of the glass tube 20 is connected, by a riser-pipe 22, with 5 one of the oil-channels 11. The pipe 22 and the upper part of the glass tube are normally filled with air, which is compressed, through the pipe 22, by the oil. The lower parts of the glass tube and the pipe 21 are filled with 10 water of condensation from the turbine-casing. When the steam-pressure and the water-pressure are equal the surface of the water in the tube 20 will be on a level with the horizontal part of the pipe 21, and any 15 difference in the pressures in question will be indicated by the water-level rising above or falling below this median point. A scale 23 may be fixed adjacent the glass tube to indicate the degree of difference in pressures. 20 Since the oil in the passages 11 is maintained at a substantial pressure above that of atmosphere, there is a constant outward flow of oil to the bearings, this oil escaping at the outer ends of the bearings. In order 25 that the oil may not be lost, but may be continually collected and returned to the bearings, an oil-tight cap 27 is fixed at the outer end of each sleeve-bearing 5, and the oil which escapes from the bearings is whirled 30 from the thrust-collars 26 against the walls of the caps, and is then drained from the bottoms of the caps through return pipes 28, which conduct it back into the reservoir 6. The reservoir is replenished, when necessary, 35 by introducing oil through a filler-opening 29, which is closed by a suitable plug and is formed, for convenience, in one of the bearing-caps 27.

Since what little leakage may occur 40 through the passage 24 is leakage of water outwardly from the turbine-casing, this water will mingle with the oil passing through the bearings and will finally be conducted to the reservoir 6 with the returning oil. The outlet-pipe 8 communicates with 45 the reservoir at a point somewhat above the bottom of the latter, so that a space is afforded in which such water may collect and be separated from the oil, and at suitable 50 intervals the water together with any sediment or spent oil, may be drawn off from the reservoir through a tap 30.

The pressure of the exhaust-steam within 55 the turbine-casing tends to rise and fall according to the volume and temperature of the steam by which the turbine is actuated, and under most conditions of operation the speed of the turbine varies in accordance with the same factors, the speed and the exhaust-pressure thus rising and falling together. Since the pump 7 is driven by the 60 turbine-shaft, its speed of operation rises and falls with that of the turbine, and hence the volume of oil which is pumped rises and falls coincidently. It will be apparent,

therefore, that even if the escape-opening, from the conduit by which the oil is delivered from the pump to the bearings, be fixedly adjusted in size, the apparatus will nevertheless tend to automatically secure the 70 desired result of approximately equalizing the oil-pressure and the steam-pressure, for the reason that as the steam-pressure rises the corresponding rise in the speed of the turbine and of the oil-pump causes an increased 75 flow of oil which, with an escape-opening of fixed size, necessarily results in an increased oil-pressure. Such an arrangement is, accordingly, within the purview of the present invention, but it is preferable to employ 80 a more sensitive and accurate device for regulating the oil-pressure, and for this purpose it is preferable to employ, as shown in the drawing, a device such as the diaphragm 14, which controls the escape-opening in accordance with the two pressures to which it is subjected in opposite directions. 85

The invention is not limited to the embodiment thereof herein described and illustrated in the accompanying drawings, but it may 90 be embodied in various other forms within the nature of the invention as it is defined in the following claims.

The invention claimed is:

1. In combination with the casing and the 95 shaft of a steam-turbine or the like, and a shaft-bearing subject, at one end, to the pressure in the casing; means for forcing lubricant continuously into the bearing adjacent said end thereof; and means for automatically maintaining the pressure of the lubricant at an approximately constant slight difference from the pressure in the casing. 100

2. In combination with the casing and the shaft of a steam-turbine, or the like, and a 105 shaft-bearing subject, at one end, to the pressure in the casing; a conduit for introducing lubricant into said bearing; means for forcing constantly, into said conduit, a surplus of lubricant under pressure; a waste-valve through which excess lubricant escapes; 110 a member connected with and controlling said valve, said member being subjected, in opposite directions, to the pressure of the lubricant in the conduit and pressure of the fluid in the casing; and means for subjecting said member to an adjustable constant force in aid of one of said pressures. 115

3. In combination with the casing and shaft of a steam-turbine or the like, and a 120 shaft-bearing subject, at its ends, to different pressures and at one end to the pressure in the casing; a conduit for introducing lubricant into said bearing; means for forcing constantly, into said conduit, a surplus of 125 lubricant under pressure; a waste-valve through which the excess lubricant escapes actuated by the difference between the higher pressure to which the end of the bearing is subjected and the pressure in the conduit; 130

and means for adjusting the waste-valve to vary the pressure difference required to actuate the same.

4. In combination with the casing and the shaft of a steam-turbine or the like, and a shaft-bearing subject, at one end, to the pressure in the casing; a conduit for introducing lubricant into said bearing; means for forcing constantly, into said conduit, a surplus of lubricant under pressure; a waste-valve through which the excess lubricant escapes; a member connected with and controlling said valve, said member being subjected, in opposite directions, to the pressure of the lubricant in the conduit and the pressure of the fluid in the casing, so as to maintain automatically a predetermined relation between said pressures; and means adjustable by the operator for supplementing the pressure upon the member in one direction.
5. In combination with the casing and the shaft of a steam-turbine or the like, and a shaft-bearing subject, at one end, to the pressure in the casing; means for forcing lubri-

cant continuously into the bearing adjacent 25 said end thereof; adjustable means for automatically maintaining a predetermined relation between the pressure of the lubricant and the pressure in the casing; and devices for indicating said pressure relation.

6. In combination with the casing and the shaft of a steam-turbine, or the like, and a shaft-bearing subject, at one end, to the pressure in the casing; a conduit for introducing lubricant into said bearing; a reservoir; a pump for drawing a surplus of lubricant from the reservoir and introducing it under pressure to the conduit; an escape valve for returning the excess lubricant from the conduit to the reservoir; a diaphragm controlling the escape valve and subject on one side to the pressure of the lubricant in the conduit and on the other side to the pressure in the casing; and an adjustable spring for supplementing the pressure on one side of 45 the diaphragm.

OLIVER D. H. BENTLEY.
